AIR CIRCULATOR FOR STOVES

Walter B. Czaja, Chicago, Ill.

Application January 31, 1942, Serial No. 428,987

9 Claims. (Cl. 126—110)

The present invention relates to air circulators for stoves and has for its principal object the provision of a device insertable within a stove for the purpose of heating therein the air and drawing the same off and expelling the same to the dwelling.

A still further object of the present invention is the provision of a device of the character stated, which may be provided with a plurality of ducts, through some of which the air is drawn into the device to be heated, and through others the heated air may be drawn by suction and expelled into the dwelling.

A still further object of the present invention is the provision of an air circulator for stoves for the purpose of utilizing the temperature of combustion gases, which would otherwise escape into the chimney, for heating the air in the air circulator and thereupon drawing the same off into the dwelling by means of suction.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views,

Fig. 1 is a vertical cross-sectional view through a stove with the present device shown therein in elevation in an operative position;

Fig. 2 is an enlarged cross-sectional view on line 2—2 of Fig. 1;

Fig. 3 is an enlarged cross-sectional view on line 3—3 of Fig. 1;

Fig. 4 is an enlarged top plan view of the air circulator; and

Fig. 5 is an enlarged cross-sectional view therethrough on a horizontal plane.

Referring in detail to the present drawing there is shown therein a stove 10, provided adjacent its upper end with a laterally extending flue section 11, to which normally a usual flue is adapted to connect and through which smoke and combustion gases are adapted to escape into the chimney. The air circulator generally indicated by 12 in Fig. 1, consists of an oblong tubular housing made by a pair of vertical side walls 13 and a pair of spaced horizontal walls 14. Side walls 13 adjacent their juncture with horizontal walls 14 are tapered as at 15.

Positioned within said housing of the air circu-

lator, and in a spaced relation, is a pair of partition walls 16, which, by means of their angularly disposed legs 17 are rigidly affixed to horizontal walls 14. Said partition walls 16 divide the tubular housing of the air circulator into a pair of outer air ducts 18, disposed adjacent side walls 13, and a central duct 19.

The inner ends of side walls 13 and their tapers 15 are joined to form a semi-circular seal 20, and to further complete the seal of the inner end of the tubular housing of the air circulator 12, the inner ends of horizontal walls 14 thereof are trimmed to form semi-circles 21, which by their margins join the adjacent circular marginal edges 15 of tapers 15. The inner ends of partition walls 16 terminate short of the circular formations of inner ends of side walls 13, tapers 15 and horizontal walls 14, as at 22. The air chamber defined by the circular inner ends of said side walls 13, tapers 15 and inner ends of horizontal walls 14, constitutes a header 23.

The outer ends of side walls 13 and their tapers 15 terminate short of the outer ends of horizontal walls 14 and partition walls 16, by virtue of which arrangement said horizontal walls 14 and partition walls 16 form an extension 24 at the outer ends thereof, for duct 19, for the purpose hereinafter stated.

Intermediately of the two ends of the air circulator horizontal walls 14 are provided with aligned longitudinal slots 25. The marginal edges of horizontal walls 14 defined by said slots 25 are rigidly connected by wall 26, for the purpose of increasing the radiation surface for duct 19.

The device further includes a horizontal pipe 27, within which air circulator 12 is positioned centrally thereof and rigidly maintained therein by means of a plurality of supporting lugs 28. The inner end of pipe 27 is insertable upon flue section 11, whereby the two frictionally inter-engage, and thereby maintain pipe 27 and air circulator 12 in an operative position with respect to stove 10.

The outer end of pipe 27 is provided with a rigidly formed and inwardly extending seal plate 29, which, by its inner marginal edge frictionally engages the perimeter of air circulator 12 substantially at the point of outer termination of side walls 13, as is seen in Fig. 1. Thus extension 24 extends outwardly and beyond said sealing plate 29. Flue 30 is rigidly affixed to pipe 27 and extends upwardly and above air circulator 12 and connects with chimney for providing passage of smoke and combustion gases from stove 10.

Insertable in any convenient manner upon ex-

tension 24 and in a rigid frictional engagement therewith, is an air pump casing 31, which contains usual air suction plates 32 positioned upon shaft 33, which is rotated by means of an electric motor 34. At the periphery of casing 31 an opening 35 is located for the purpose of expelling air therefrom which in turn was sucked out from duct 19.

From the hereinabove description it will be seen that in an operative position of air circulator 12, a substantial portion of its inner end remains within stove 10 and adjacent its upper end, and disposed above its fire pot. The heated air, smoke and combustion gases circulate around said air circulator 12, both around its portion remaining within the stove as well as its portion positioned within flue section 11 and pipe 27. Thus the air remaining within ducts 18 and 19 as well as in the header 23 will be heated. The heating of air within duct 19 is further facilitated by means of the radiation wall 26 within slots 25.

Assuming that air pump 32 is in operation, suction of air is created in duct 19, drawing the same from the air circulator into the dwelling atmosphere through opening 35 as long as said air pump 32 operates, and continuous suction upon the air in duct 19 will be had, thereby causing air from the dwelling to enter into ducts 18, and through the opening made at the outer ends of side walls 13 and tapers 15 and the adjacent faces of partition walls 16. The air entering through these openings will be caused to flow along ducts 18 and towards header 23, and in the direction indicated by arrows in Fig. 5. The flowing air will of course be heated by the combustion gases circulating around the air circulator, as indicated by arrows in Fig. 1. The air flowing into header 23 will be caused to enter duct 19 by virtue of suction thereon exerted by pump 32 and reverse its direction indicated by arrows in Fig. 5, until it enters pump casing 31 and until it is expelled therefrom by fans 32 and through opening 35 into the dwelling.

It is observed, that since the outer faces of side walls 13, tapers 15 and horizontal walls 14 are exposed to the action of the temperature of the circulating combustion gases around air circulator 12, the flowing air, both in ducts 18 and duct 19 will be constantly heated as long as the same remains within the air circulator.

While there is described herein a preferred embodiment of the present invention, it is nevertheless to be understood that minor changes may be made therein without departing from the spirit and scope of the invention as claimed.

What I claim as new is:

1. An air circulator comprising an elongated hollow member including a pair of spaced horizontal walls and a pair of side walls, said horizontal walls and said side walls merging at one end of said member for forming a sealed header, and a pair of spaced partition walls vertically disposed in said member, the inner ends of said partition walls terminating short of said header, said partition walls in conjunction with said side walls defining a pair of lateral air inlet ducts and a central outlet duct, the outer ends of said horizontal and partition walls extending beyond the corresponding termination of said side walls. 70

2. In combination with a stove including a flue section, a pipe engageable and supportable by said flue section, an elongated hollow member positioned within said pipe and extending through said flue section into the stove, said mem- 75

ber having an open and a sealed end, a flue extending from said pipe, the outer open end of said member extending beyond said pipe, means for causing flow of air into and out of said member through its open end, means for rigidly supporting said member within said pipe, and a sealing plate extending from the outer end of said pipe and engaging the perimeter of said member adjacent its open end.

10 3. In combination with a stove including a flue, an elongated hollow member having a sealed and an open end positioned within said flue and extending into the stove by its sealed end, the outer open end of said member extending beyond said flue, partition walls within said hollow member and in a longitudinal relation therewith, said partition walls in conjunction with the walls of said member defining air inlet ducts and an outlet duct, said partition walls terminating short of the sealed end of said member for facilitating an unobstructed flow of air from said inlet ducts into said outlet duct, means at the open end of said member and in association with said outlet duct for forcing the air into said inlet ducts and out of said outlet duct, and means for rigidly supporting said member within said flue.

4. In combination with a stove including a flue, an elongated hollow member having a sealed and an open end positioned within said flue and 30 extending into the stove by its sealed end, the outer open end of said member extending beyond said flue, partition walls within said hollow member and in a longitudinal relation therewith, said partition walls in conjunction with the walls of said member defining air inlet ducts and an outlet duct, said partition walls terminating short of the sealed end of said member for defining a continuous passage for air from said inlet ducts into said outlet duct, means at the open end of said member and in association with said outlet duct for forcing the air into said inlet ducts and out of said outlet duct, and means for rigidly supporting said member within said flue.

5. In combination with a stove including a flue, 45 an elongated hollow member including a pair of horizontal walls and a pair of vertical walls, said walls at one end thereof being joined to form a seal at one end of said member, a pair of partition walls within said member and in a substantially parallel relation with said vertical walls, said partition walls in conjunction with the walls of said member defining a pair of outer air ducts and a central air duct, said partition walls terminating short of the sealed end of said member for defining a continuous passage for air from said outer ducts into said central duct, said partition walls by their outer ends and the adjacent portions of said horizontal walls extending beyond the outer ends of said side walls and said outer air ducts for defining a stud, said sealed end of said member extending within the stove, means in said flue for supporting said member in an operative position, a sealing plate extending from the outer end of said flue and engaging the perimeter of said member adjacent the outer termination of said vertical walls, and means positioned upon said stud for drawing air into said member through said outer air ducts and expelling the same through said central air duct.

6. As an article of manufacture, an air circulator for stoves comprising an elongated hollow member including a pair of horizontal walls and a pair of vertical walls, said walls at one end thereof being joined to form a seal at one end of said member, and a pair of partition walls within

said member and in a substantially parallel relation with said vertical walls, said partition walls in conjunction with the walls of said member defining a pair of outer air ducts and a central air duct, said partition walls terminating short of the sealed end of the said member for defining a continuous passage for air from said outer ducts into said central duct, said partition walls by their outer ends and the adjacent portions of said horizontal walls embraced by said partition walls extending beyond the outer ends of said side walls.

7. As an article of manufacture, an air circulator for stoves comprising an elongated hollow member substantially rectangular on transverse cross-section, the walls of said member at one end thereof being joined to form a seal, and a pair of partition walls within said member and in a substantially parallel relation with a pair of oppositely disposed walls of said member for defining a pair of outer air ducts and a central duct, said partition walls terminating short of said seal for defining a continuous passage for air from said outer ducts into said central duct, said partition walls by their outer ends and the adjacent portions of the other pair of oppositely disposed walls of said member embraced by said partition walls extending beyond the outer ends of said first named pair of said oppositely disposed walls.

8. An air circulator comprising an elongated hollow member including a pair of spaced hori-

- zontal walls and a pair of side walls, said horizontal walls and said side walls merging at one end of said member for forming a sealed header, a pair of spaced partition walls vertically disposed in said member, the inner ends of said partition walls terminating short of said header, said partition walls in conjunction with said side walls defining a pair of lateral air inlet ducts and a central outlet duct, the outer ends of said horizontal and partition walls extending beyond the corresponding termination of said side walls for defining an extension, and means receivable by said extension for drawing the air entering said header through said inlet air ducts.
- 15 9. An air circulator comprising an elongated hollow member including a pair of spaced horizontal walls and a pair of side walls, said horizontal walls and said side walls merging at one end of said member for forming a sealed header, a pair of spaced partition walls vertically disposed in said member, the inner ends of said partition walls terminating short of said header, said partition walls in conjunction with said side walls defining a pair of lateral air inlet ducts and a central outlet duct, the outer ends of said horizontal and partition walls extending beyond the corresponding termination of said side walls for defining an extension, and an air pump receivable by said extension for drawing the air entering said header through said inlet air ducts.
